CHILD'S COWBOY SUIT

Hazel Delle Knight, Seattle, Wash.

Application January 19, 1949, Serial No. 336

Term of patent 3½ years

(Cl. D3—17)

To all whom it may concern:

Be it known that I, Hazel Delle Knight, a citizen of the United States of America, residing at Seattle, in the county of King and State of Washington, have invented a new, original, and ornamental Design for a Child's Cowboy Suit, of which the following is a specification, reference being had to the accompanying drawings, forming part thereof.

In the drawings Figure 1 is a front elevational view of a child's cowboy suit showing my new design.

Fig. 2 is a rear elevational view of the same.

I claim:

The ornamental design for a child's cowboy suit, as shown.

HAZEL DELLE KNIGHT.
